CLAIM

The ornamental design for a kids swim vest with cape, as shown and described.

DESCRIPTION

FIG. 1 is a front perspective view of the kids swim vest with cape, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the kids swim vest with cape, in an alternate configuration; and,

FIG. 10 is a front perspective view of the kids swim vest with cape, in an environment of use.

The broken lines in FIGS. 1-9 illustrate portions of the kids swim vest with cape in which the design is embodied and form no part of the claimed design. The broken lines illustrating a person in FIG. 10 are shown for completeness of illustration and form no part of the claimed design.

1 Claim, 10 Drawing Sheets
